UNITED STATES PATENT OFFICE.

JOHN O. McKEAN, OF WESTFIELD, MASSACHUSETTS, ASSIGNOR TO FOSTER MACHINE COMPANY, OF WESTFIELD, MASSACHUSETTS, A CORPORATION OF MASSACHUSETTS.

COMBINED YARN CLEARGER AND TENSION DEVICE.

1,423,864.

Specification of Letters Patent. Patented July 25, 1922.

Application filed April 1, 1921. Serial No. 457,728.

To all whom it may concern:

Be it known that I, JOHN O. McKEAN, a citizen of the United States, and resident of Westfield, in the county of Hampden and 5 State of Massachusetts, have invented a new and useful Improvement in a Combined Yarn Clearer and Tension Device, of which the following is a specification.

The object of my invention is to provide 10 a combined yarn clearer and tension which will have novel features of construction, whereby the yarn may be efficiently cleared and a suitable tension applied thereto.

A further object is to provide a device of 15 this character in which the horizontally disposed knives on which the discs rest are provided with a plurality of edges, the knives being rotatively adjustable in their holder whereby different edges may be presented 20 to the discs.

A further object is to provide a device 25 of the above character in which either the holder for the knives or the holder for the weighted discs may be automatically reciprocated to move the points of contact between the discs and knives so that the localized wear upon the knives will be reduced to a minimum and the life of the device materially increased.

30 A practical embodiment of my invention is represented in the accompanying drawings, in which,

Fig. 1 represents a plan view of the device and its adjacent parts.

35 Fig. 2 represents a side elevation of the same.

Fig. 3 represents a front end elevation.

The rotary cam shaft is denoted by 1 and its cam by 2. A reciprocating cam 40 bar 3 is provided with studs or rollers 4 and 5 engaging the periphery of the cam 2. A fixed horizontally arranged bar 6 is located above the reciprocating cam bar 3.

A knife holder uprises from and is fixed 45 to the reciprocating cam bar 3. The upright portion 7 of this holder is provided with a collar 8 surrounding the cam bar 3, and a yoke 9 partially surrounding the bar 6 and slidable along the same. A set 50 screw 10 serves to fasten the collar 8 in the proper adjusted position on the cam bar 3. The upright 7 of the knife holder is provided with a cross-bar 11 from which project a horizontal series of knives 12 ar- 55 ranged in pairs. Each of these knives is provided with a plurality of edges, (in the

present instance three) and it is rotatively adjustable in the arm 11 of the knife holder, preferably by providing the knife with a round shank located in a hole through said arm 11. A set screw 13 is provided for each of the knives 12 to secure the knife in its properly adjusted position.

At the inner end of the arm 11 of the knife holder I preferably provide a yoke, 65 the resilient arms of which are denoted by 14 and 15, which arms carry the blades 16 and 17 of a stub catcher. An adjusting screw 18 engages the resilient arms 14 and 15 to adjust the width of the slot between 70 the blades 16 and 17 of the stub catcher.

The upright 19 of a weighted disc holder is provided with a yoke 20 which surrounds the reciprocating cam bar 3, and a hub 21 which surrounds the fixed bar 6. A set 75 screw 22 is arranged to secure the upright 19 of the weighted disc holder in its adjusted position on the bar 6, it being understood that the cam bar 3 freely reciprocates through the yoke 20 of the said disc holder. 80

To the top of the upright 19 I secure the shank 23 of a T-shaped arm, the lateral branches of which are denoted by 24, 25. These branches 24, 25 are provided with a series of depending pins 26 which prefera- 85 bly project into the plane of the horizontally disposed knives 12 between the two knives of each pair.

A weighted disc 27 is loosely mounted on each of the depending pins 26 and rests 90 upon its pair of knives 12 with a four point contact except when the yarn is passing between the weighted disc and the knives.

These discs are preferably arranged in different transverse planes so as to offset 95 certain of the discs from the others. In the present instance I have shown the discs as arranged in a curved line.

The arm 25 of the disc holder may be provided with a leading-in guide 28 for 100 properly directing the yarn to the first disc, and the arm 11 of the knife holder may be provided with a guide 29 for leading the yarn from the last disc to the stub catcher.

From the above description it will be seen 105 that by the rotary movement of the shaft 1, the cam 2 causes the reciprocation of the cam bar 3 and thereby the reciprocation of the knives 12 to constantly change their points of contact with the weighted discs 110 27. This constant movement of the knives will reduce the localized wear on their

edges which contact with the discs to a minimum.

It is obvious that instead of reciprocating the knife holder, the disc holder could just 5 as readily be reciprocated to produce the same effect.

When the contact edges of the knives become unduly worn, the knives may be 10 rotatively adjusted to bring a new set of contact edges into coaction with the discs. By this adjustment, the life of each knife is materially increased. When the knives become 15 useless or ineffective they may be readily removed and replaced by new knives, thus materially reducing the cost of the yarn clearer and tension device as a whole.

It is evident that various changes may be 20 resorted to in the construction, form and arrangement of the several parts without departing from the spirit and scope of my invention; hence I do not wish to limit myself to the particular construction herein shown and described, but

25 What I claim is:—

1. A combined yarn clearer and tension, comprising horizontally disposed parallel knives, and a weighted disc resting thereon.

2. A combined yarn clearer and tension, 30 comprising horizontally disposed parallel knives and weighted discs resting thereon.

3. A compound yarn clearer and tension, comprising horizontally disposed parallel knives, each having a plurality of edges, 35 and a weighted disc resting on said knives.

4. A combined yarn clearer and tension, comprising horizontally disposed parallel knives, each having a plurality of edges, and weighted discs resting on said knives.

40 5. A combined yarn clearer and tension, comprising horizontally disposed knives, each having a plurality of edges, and a weighted disc resting on said knives, the knives being rotatively adjustable to present different edges to said disc.

45 6. A combined yarn clearer and tension, comprising horizontally disposed knives, each having a plurality of edges, and weighted discs resting on said knives, the knives being rotatively adjustable to present different edges to said discs.

50 7. A combined yarn clearer and tension, comprising horizontally disposed knives, a weighted disc resting on said knives, holders for said knives and disc, and means for automatically reciprocating one of said holders, to move the points of contact between the disc and knives.

60 8. A combined yarn clearer and tension, comprising horizontally disposed knives, weighted discs resting on said knives, holders for said knives and discs, and means for automatically reciprocating one of said holders, to move the points of contact between 65 the discs and knives.

9. A combined yarn clearer and tension, comprising horizontally disposed knives, each having a plurality of edges, a weighted disc resting on said knives, holders for said knives and disc, said knives being rotatively adjustable in their holder to present different edges to said disc, and means for automatically reciprocating one of said holders to move the points of contact between the disc and knives. 70

10. A combined yarn clearer and tension, comprising horizontally disposed knives, each having a plurality of edges, weighted discs resting on said knives, holders for said knives and discs, said knives being rotatively adjustable in their holder to present different edges to said discs, and means for automatically reciprocating one of said holders to move the points of contact between the discs and knives. 75 80

11. A combined yarn clearer and tension, comprising a pair of horizontally disposed parallel knives, and a weighted disc resting thereon. 85

12. A combined yarn clearer and tension, comprising a plurality of pairs of horizontally disposed parallel knives, and a weighted disc resting on each pair of knives. 90

13. A combined yarn clearer and tension, comprising horizontally disposed knives, their holder, a series of weighted discs resting on said knives, and a holder for said discs having depending pins for loosely mounting the discs. 95

14. A combined yarn clearer and tension, comprising horizontally disposed knives, their holder, a series of weighted discs resting on said knives, and a holder for said discs having depending pins for loosely mounting the discs, certain of the discs being offset in transverse planes from the other discs. 100 105

15. A combined yarn clearer and tension, comprising horizontally disposed knives, their holder, a series of weighted discs resting on said knives, a holder for said discs having depending pins for loosely mounting the discs, and means for automatically reciprocating one of the holders to move the points of contact between the discs and knives. 110 115

16. A combined yarn clearer and tension, comprising horizontally disposed knives, their holder, a series of weighted discs resting on said knives, and a holder for said discs having depending pins for loosely mounting the discs, the disc holder having a leading in guide eye for the yarn, and the knife holder having a stub catcher for the yarn. 120 125

In testimony that I claim the foregoing as my invention, I have signed by name this 24th day of March 1921.

JOHN O. McKEAN.
